US0D1067574S

(12) **United States Design Patent** (10) **Patent No.:** **US D1,067,574 S**
(45) **Date of Patent:** **** Mar. 18, 2025**

(54) **SPLICED WINCH THIMBLE**

(71) Applicant: **MercuryPM Pty Ltd**, Kilsyth (AU)

(72) Inventor: **Stephen Handbury**, Kilsyth (AU)

(73) Assignee: **MERCURYPM PTY LTD**, Kilsyth (AU)

(**) Term: **15 Years**

(21) Appl. No.: **29/864,851**

(22) Filed: **Jun. 23, 2022**

(30) **Foreign Application Priority Data**

Jun. 17, 2022 (AU) 202213517

(57) **CLAIM**

The ornamental design for a spliced winch thimble as shown and described.

DESCRIPTION

FIG. 1 is a perspective view of a spliced winch thimble, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

1 Claim, 7 Drawing Sheets
